MILTON H. SHOENBERG, OF SAN FRANCISCO, CALIFORNIA.

METHOD OF ELECTRIC THERMAL CONTROL.

1,393,323.

Specification of Letters Patent. Patented Oct. 11, 1921.

Application filed December 27, 1919. Serial No. 347,735.

To all whom it may concern:

Be it known that I, MILTON H. SHOENBERG, a citizen of the United States, and a resident of the city and county of San Francisco, State of California, have invented new and useful Improvements in Methods of Electric Thermal Control, of which the following is a specification.

My invention has for its principal object 10 the control of terminal electrical apparatus in which current consumption is utilized in overcoming resistance, as in heaters, motor circuits and the like, and consists of the method by which the flowing current is 15 utilized through a heating element, or resistance wire, the expansion of which wire interrupts the path of a previously shunted circuit through the said wire, causing by the said interruption a cutout of the said 20 shunted circuit and more current to flow through the expansion member, or through the operating element of a remote device, as for example—the thermostat wire of the switch in my co-pending applications, Serial 25 No. 347,732 and Serial No. 347,734, filed December 27, 1919, whereby the switch is automatically tripped and automatically snapped into its open position, thereby cutting out the terminal circuit from the re- 30 mote device.

By referring to the accompanying drawings my invention will be made clear.

The figure illustrates my method as applied to a water heater, but it is to be understood that it is equally applicable to any other form of apparatus in which a variation in temperature will occur, or may be caused to occur in an expandible element.

A water heater is indicated by numeral 40 1, provided with an inlet at 2, and an outlet at 3, and having an electrical resistance heater coil 4, adapted to be energized through the connections 5 and 6. The latter is in electrical connection with the metallic support 7, which is cut away at 8 to provide ready access for circulating water to, and heat dissipation from, the expandible wire 9. This latter is electrically connected to the support 7 at one end as 10, and at the opposite end as 11, to a lever or spring member 12, having also a contact point at its end 13. The latter is adapted to normally electrically communicate with the circuit wire 14, and the member 12 is 55 in electrical connection with the circuit wire 15.

The wires 5, 14 and 15 may be of any length required and are connected through a device such as is set forth in my above mentioned applications and diagrammatically shown herewith in the figure, and wherein the switch blades 16, 17 are adapted to close, or interrupt the circuit from the main leads 19, 18 through suitable operating connections. The position of closure, however, of said switch blades being retained only at such time as the latch member 20 is in its down or restrained position due to the contracted condition of the expandible wire 21.

It will be seen that when the switch blades 16 and 17 respectively cross-connect the wires 19, 5 and 14, 18, and are held in such contact by the latch member 20, wires 17, 14, 13, 9, 7, 6, 4, 5, 16, 19, form the path of current flow that will energize the heating coil 4 and also the thermal wire 9 in series therewith, that there is much less flow through the wire 21 during the time that the thermal wire 9 is contracted and contact made at the point 13, but upon the expansion of the wire 9 due to its heat not being dissipated with sufficient rapidity there will be a separation of the points and a breaking of the circuit at 13, causing the entire current which passes through the heating coil 4 to the wire 9 to also be passed through the thermal wire 21 in the remote device. This will set up a corresponding increase in temperature therein and coincident therewith its expansion and the release of the latch 20 and of the switch blade 17, and its connected or associate switch blade 16, and a snapping of the switch blades into the position 23, 22. This is accomplished by suitable spring connections and as indicated in the above entitled co-pending applications.

The operation is as follows:

To operate the heater the switch blades 17, 16 are thrown into the full line position indicated, at which point they are automatically retained by the latch 20. If for any reason it is desired to turn the heater off, they are thrown into the dotted positions 23, 24, and may be turned on and off as often as desired from the positions 16, 17 to 23, 24, or vice versa.

When in full line position the heating coil 4 will be energized by current flowing through the leads 5 and 14, the water flowing from 2 around the coil 4, the thermal wire 9 and out through the outlet 3 will be

heated due to the electrical resistance of the parts within the heater casing 1. This water in transit will extract the heat from the thermal wire 9 at a rate sufficient to 5 keep its temperature lower than would be the case if the circulating water was stationary, or absent, therefore any interruption in the flow of the water, or in case of its boiling away from the upper part of the 10 casing 1, will result in the wire 9 becoming excessively hot and coincident therewith its expansion and an interruption of the circuit between 14 and 12 at the contact point 13. This will throw the entire current 15 through the thermal wire 21 causing its expansion, which releases the latch 20 and causes the switch blades 16, 17 to snap into the positions 25, 22 thereby interrupting the current through the heating coil 4 and other 20 parts and protecting them from any damage due to excess heating, or excess current flow.

I claim:

1. A method of electric thermal control

consisting of energizing a terminal device 25 through two parallel paths and a return, one of said paths adapted to be interrupted on an excess of heat in said terminal device whereby a greater current is caused to flow over the other path to thereby cause 30 in a remote device in said other path actuation to release a spring actuated switch to open the energizing circuit.

2. A method of electric thermal control 35 consisting of energizing a terminal device partly through an expansion element adapted to release a switch when an excess of current flows therethrough and partly through a lead paralleled thereto and said terminal device including an expansion element adapted to break the circuit through said lead when said terminal element exceeds a predetermined temperature.

In testimony whereof, I have hereunto set my hand at the city and county of San 45 Francisco, California.

MILTON H. SHOENBERG.
